MICROMETER

Edward E. Willis, Lewistown, Pa., assignor of fifteen per cent to William B. Heaps, Mifflin, Pa.

Application September 22, 1941, Serial No. 411,918

3 Claims. (Cl. 33—165)

This invention relates to improvements in micrometers.

The object of the invention is to provide a micrometer which is especially designed for measuring objects varying considerably in size, so that the same may be rapidly and slidably adjusted to approximately the proper size, while the finer and final adjustment is made by a threaded connection.

Another object of the invention is to provide a structure of this character in which the usual wear in threaded adjustments is greatly reduced in measuring objects that vary considerably in size, whereby the final adjustment may be made to obtain a more accurate measurement.

A further object of the invention is to provide means whereby any wear in the final threaded adjustment is compensated for, resulting in a more accurate measurement of the objects; and, at the same time, producing a simple micrometer which can be cheaply manufactured.

In the accompanying drawing,

Figure 1 is a side elevation of my improved micrometer;

Figure 2 is a longitudinal sectional view, taken on the line 2—2 of Figure 1, showing the parts in position for the final adjustment;

Figure 3 is a longitudinal sectional view of the outer rotating member, showing the thread engaging and disengaging members in full lines;

Figure 4 is a side elevation of the thread engaging members in their separated position.

Referring now to the drawing, 1 represents the yoke having the usual anvil 2 on the inner face of the outer end thereof. The opposite end of the anvil is provided with a large barrel 3, having a bore 4 terminating in a small opening 5 arranged in exact alinement with the anvil 2. The barrel is provided with a transverse slot 6, in which is arranged the locking nut 7, which will be hereinafter more fully described. The barrel 3 has rigidly secured to the outer end thereof the tube 8, having a bore 9 therein of the same size as the bore 4 and forming a continuation thereof. The inner end of the tube has marked thereon a scale 10, whereby calculations are made. The outer end of the tube is provided with four cut-out portions 11 forming four spring arms 12, which have their inner faces threaded at 13, and their extreme ends beveled, as indicated at 14. Passing through the bore of the tube or sleeve 8 is a tube 15 having one end threaded, as indicated at 16, and the opposite end provided with four cut-out portions or slots 17, and beyond these cut-out portions, the tube is enlarged, as

indicated at 18. The tube 15 passing within the tube 8, and the lock nut 7 is threaded upon the threads 16.

The inner end of the bore 19, of the enlarged end 18, is beveled at 20 and adapted to engage the beveled ends 14 of the spring arms 12. It will thus be seen that, as the tube 15 is forced outwardly by the lock nut 7, the spring arms are forced inwardly into the cut-out portion 17 by engagement with the beveled portion 20 of the member 18. Sliding on the tube 8 is the handle 21, which is provided with a closed end 22. Carried by the closed end is a projection 23, upon which is mounted an operating knob 24, having a slip connection 25 with the projection 23, whereby the handle 21 can not be turned beyond a certain resistance.

The closed end of the tube is provided with an outwardly extending rod 26, which is of a diameter to freely pass through the bore of the tube 15, and is screw threaded, as indicated at 27. The outer end of the rod 26 is reduced, as indicated at 28, and extends through the opening 5 in the outer end of the barrel 3, as clearly shown in Figure 2 of the drawing.

In operation, the lock nut 7 is turned on the threads 16 of the tube 15 to the right forcing the tube outwardly so as to bring the spring arms 12 from engagement with the beveled portion 20 of the enlarged end 18, whereby they are disengaged from the threads 27, of the rod 26, and the handle 21 is free to slide on the tube 8 to bring the reduced end 28 in approximately the proper distance in respect to the anvil. The lock nut then is turned to the left drawing the tube 15 inwardly and locking the spring arms into threaded engagement with the handle. By a further turning of the handle, it will be seen that the same can be finely adjusted.

Having thus described my invention, what I claim is:

1. A micrometer, comprising a yoke, an anvil at one end, a cylindrical barrel carried by the opposite end of the yoke and provided with a transverse slot intersecting the bore thereof, a tube carried by one end of the barrel and having a scale on the barrel and its opposite end provided with internally threaded outwardly held spring arms, a sleeve sliding within the tube and provided with a threaded end extending into the bore of the barrel and provided with slots to receive said spring arms, an adjusting nut in the slot of the barrel and threaded thereon, a handle slidably mounted on the tube and having a rigid rod telescoping within the sleeve and provided

with external threads adapted to be engaged by the threads of the spring arms, and a beveled face carried by the inner sleeve for engaging the spring arms and forcing them into engagement with the threads on the rod.

2. A micrometer, comprising a yoke, an anvil at one end, a barrel carried by the opposite end of the yoke and provided with a transverse slot intersecting the bore thereof, a tube rigidly carried by one end of the barrel and having a scale thereon adjacent one end and its opposite end provided with internally threaded outwardly held spring arms, a sleeve sliding within the tube and provided with a threaded end extending to the bore of the barrel and provided with slots to receive said spring arms, a nut in the slot of the barrel and threaded thereon, a handle slidably mounted on the rigid tube and having a rigid rod telescoping within the sleeve and externally threaded, a beveled face carried by the sleeve upon the longitudinal movement thereof to cause the threads of the spring arms to engage the threads of the rod, and a rotating operating rod carried by the handle and having a frictional engagement therewith.

3. A micrometer, comprising a yoke, an anvil

at one end, a barrel carried by the opposite end of the yoke and provided with a transverse slot intersecting the bore thereof, a tube rigidly carried by one end of the barrel, internally threaded outwardly held spring arms carried by the outer end of the tube, a sleeve sliding in said tube and having a threaded end extending into the bore of the barrel and provided with slots to receive said spring arms, a lock nut arranged on the threads within the slot in the barrel, the sleeve having an enlarged portion beyond its slots provided with a beveled inner wall, a handle telescoping on the rigid tube and provided with an internal screw threaded rod passing through the sleeve and having a reduced outer end passing through the opening in the outer end of the barrel, the ends of the spring arms having beveled outer surfaces and screw threaded inner surfaces, the beveled inner wall of the sleeve contacting with the beveled outer surfaces of the spring arms to releasably hold said arms in engagement with the screw threads of the rod, and the lock nut being adapted to move the sleeve within the tube to cause the engagement or disengagement of the spring arms with the threads of the rod.

EDWARD E. WILLIS.
